Fig. 4

Fig. 6

Fig. 5

FIGURE 1 is a front elevational view of a lather applicator for shaving cream, showing my new design.

FIGURE 2 is a side elevational view as seen from the right of FIGURE 1.

FIGURE 3 is a rear elevational view.

FIGURE 4 is a bottom plan view of the applicator shown in FIGURE 1.

FIGURE 5 is a top plan view of the applicator shown in FIGURE 1.

FIGURE 6 is an elevational view of the applicator shown in FIGURE 3 with the head portion thereof tilted to a horizontal position.

In FIGURES 1 and 2 the applicator is shown magnetically attached to a can of the aerosol type containing shaving cream, the can being shown in dotted lines. The design is shown in full lines.

I claim:

The ornamental design for a lather applicator for shaving cream, as shown and described.
